UNITED STATES PATENT OFFICE.

GEORGE P. McDONNELL, OF ST. LOUIS, MISSOURI.

SAFETY DEVICE FOR ELEVATORS.

1,408,459.

Specification of Letters Patent. Patented Mar. 7, 1922.

Application filed May 31, 1919. Serial No. 300,960.

To all whom it may concern:

Be it known that I, GEORGE P. McDONNELL, a citizen of the United States of America, a resident of the city of St. Louis, 5 in the State of Missouri, have invented certain new and useful Improvements in Safety Devices for Elevators, of which the following is a full, clear, and exact description, reference being had to the accompanying drawings, forming a part of this specification.

My invention relates to improvements in safety devices for elevators, one of the objects being to avoid the liability of serious 15 accidents, which have heretofore been caused by the elevator striking a part of a person's body or other obstructions in the elevator entrance. Accidents of the kind referred to are sometimes caused by the elevator striking a 20 person leaning from the elevator landing into the elevator shaft, for the purpose of determining the location of the elevator. In this event, the person may be struck either by the bottom of a downwardly moving elevator or by the top of the elevator moving upwardly in the shaft. Accidents have also 25 resulted from the elevator striking obstructions, such as lumber carelessly placed on the elevator landing so as to project into the 30 elevator entrance. Again, persons attempting to leave a moving elevator have been caught between the floor of the rising elevator and the top of the doorway in the elevator shaft, or if the elevator is moving 35 downwardly, a person attempting to pass through the entrance may be caught between the floor of the landing and the top of the doorway in the elevator. Furthermore, it sometimes happens that a person standing 40 inside of a moving elevator will have a portion of his arm or foot extended through the doorway in the elevator, so as to strike a stationary part of the elevator shaft.

My object is to provide a safety device, or 45 devices, whereby accidents from one or all of the above mentioned acts may be avoided. The combination I have shown to illustrate the preferred form of the invention includes a stopping device for the elevator, 50 and automatically operated members controlling said stopping device. For example, these automatically operated members may include thrust-receiving abutments in the form of vertically movable striking members 55 adapted to extend across the elevator entrance. One of these striking members may be

arranged across the doorway in the elevator cage, another may be carried by the cage and arranged above the top thereof, a third may be carried by the lower portion of the 60 cage and arranged below the floor thereof, and a fourth may be located across the elevator entrance and movably secured to the elevator shaft. These striking members are adapted to engage a part of a person's body, 65 or other member, projecting into the elevator entrance, so as to transmit movement from the elevator to the stopping device, thereby automatically stopping the elevator.

Another object is to provide a simple and 70 inexpensive means for preventing the operation of the elevator when any one of the entrance doors occupies its open position.

With the foregoing and other objects in view, the invention comprises the novel construction, combination and arrangement of parts hereinafter more specifically described and illustrated in the accompanying drawings wherein is shown the preferred embodiment of the invention; however, it is to be 75 understood that the invention comprehends changes, variations and modifications which come within the scope of the claims hereunto appended.

Fig. I is a front elevation, partly in section, illustrating an elevator mounted in a shaft, and also showing safety devices embodying the features of this invention.

Fig. II is a perspective view of the elevator cage, illustrating the safety devices 90 carried thereby.

Fig. III is a diagrammatical view of the electrically operated devices.

Fig. IV is a diagrammatical view of the operating means for the elevator, and the 95 brake for stopping the operating means so as to stop the elevator.

A designates an elevator cage, and B designates the vertical shaft in which the cage is mounted. The different floors or elevator 100 landings are designated by the characters 1, 2 and 3 (Fig. I). At each of these landings the elevator shaft is provided with an entrance normally closed by doors 4, and the elevator cage has an entrance or doorway 5 105 adapted to register with the doors 4.

A safety switch S, carried by the elevator, may be utilized to control a stopping device, as will be hereinafter described. This switch comprises a fixed contact member 6, 110 a movable contact arm 7, and a spring 8 tending to retain said arm in engagement

with the contact member 6. This switch normally occupies the closed position shown in Figs. II and III, and if it is opened, a stop device will become effective, so as to 5 quickly stop the elevator. In an emergency, this is accomplished by moving the contact arm 7 away from the relatively stationary contact 6. Before describing the stopping device under control of the safety switch, 10 I will point out the means whereby said switch is actuated to stop the elevator.

9 designates a thrust receiving abutment, or striking member, in the form of a chain arranged below the front portion of the elevator 15 and having one of its ends secured to a rigid arm, which extends downwardly from the elevator, its opposite end being secured to a bell crank lever 11 which lies below the movable contact arm 7. If the 20 chain 9 is forced upwardly, relative to the elevator, the bell crank lever will be actuated to lift the contact arm 7 from the contact 6, thereby stopping the elevator. In other words, if the chain 9 strikes an 25 obstruction while the elevator is moving downwardly, the safety switch will be automatically operated to stop the elevator.

Another operating means for the safety switch S includes a chain 12 connected to 30 the contact arm 7, and also connected to a vertical post 13 extending from one of the upper corners of the elevator. This chain 12 has a vertical portion which extends from the contact arm to a pulley 14, and a horizontal portion 12' extending from said pulley to the post 13. The horizontal portion 12' constitutes a thrust receiving abutment, or striking member, and it lies above the front portion of the elevator, where it will 35 engage a projection of any kind extending into the elevator shaft at a point above the front of the elevator. If this striking member 12' engages an obstruction while the elevator is moving upwardly, motion will be 40 transmitted through the chain 12 to the movable contact arm 7 to open the safety switch, thereby stopping the elevator.

Another means for operating the stopping switch consists of a long horizontal bar 15 45 arranged across the elevator entrance, and connected to the chain 12 by means of a relatively weak chain 16, said bar being pivoted at 17 to the elevator. 18 designates a combined guide and stop device for the free 55 end of bar 15. This bar 15, like the members 9 and 12', constitutes a thrust receiving abutment, or striking member, and it may be lifted about the axis of its pivot 17 so as to transmit movement to the chain 12, 60 thereby actuating the stopping switch S.

A safety switch S', corresponding in function to the stopping switch S, is preferably located at the bottom of the elevator shaft. This switch S' comprises a stationary con- 65 tact 6', a movable contact arm 7' and a

spring 8' normally retaining these contact members in engagement with each other. The switch S' may be opened to stop the elevator, as will be hereinafter described. 19 designates a long vertical switch operating member, preferably a chain or cable, located in the elevator shaft and connected at its lower end to the movable contact arm 7'. The upper end of this vertical operating member is connected to a counterbalance spring 20 supported by a vertically adjustable rod 21, said rod being threaded to receive a nut 22 which engages a bracket 23 in the elevator shaft. The spring 20 is placed under tension by the weight of the 70 vertical operating member 19, and since this spring tends to lift the operating member it serves as a counterbalance which enables the vertical operating member to be easily lifted. 75

The means for automatically actuating the vertical member 19 preferably comprises a series of horizontal bars 24 (Fig. I), each of which is arranged across the upper portion of an entrance to the elevator and pivoted to the elevator shaft at 25. Relatively weak chains 26 connect the free ends of the bars 24 to the vertical operating member 19. If one of the bars 24 is moved upwardly about the axis of its pivot 25, motion will 80 be transmitted to the vertical operating member 19, and thence to the movable contact member 7', so as to open the safety switch S', thereby stopping the elevator. It will be observed that each of the horizontal 85 bars 24, pivotally secured to the elevator shaft, constitutes a thrust receiving member, or striking member, adapted to be engaged by a projection of any kind extending from the front of the elevator. 90

The bars 24 may also be actuated by the elevator doors to prevent the elevator from starting when a door occupies its open position. By referring to Fig. I it will be seen that each bar 24 is notched to provide a cam 27, which normally rests upon a roller 28 carried by an elevator door. When a door is moved to its open position, roller 28 cooperates with a cam 27 to lift the bar 24, and motion is then transmitted from the bar 24 to 95 the vertical operating member 19, with the result of opening the safety switch S'. When the door is restored to its closed position, the roller 28 will be located under the cam 27 and the switch S' will then be closed 100 by the action of its spring 8'. The elevator cannot be operated when the switch S' occupies its open position, and it will therefore be understood that the bars 24 cooperating 105 with rollers 28 prevent operation of the elevator when one of the doors occupies its open position. I am aware that it is old to accomplish this particular result by the use of individual electric switches for each elevator door, but by using the combination here- 110 115 120 125 130

in shown, a single switch may be used for several elevator doors, and if the electrical elements fail to properly perform their functions, this single switch can be easily inspected for the purpose of locating the defect in the electrical appliances. Furthermore, this simple switch S' cooperates with the bars 24 to stop the elevator, as will be hereinafter pointed out.

10 From the foregoing description, assuming that the switches S and S' may be operated to stop the elevator, it will be readily understood that the safety devices herein shown are adapted to prevent accidents in the following manner:

The roller 28, cooperating with cam 27, will ordinarily prevent the elevator from starting when a door occupies its open position, but if this particular feature of the 20 device should not be used in the combination, or if it should fail to properly perform its function, accidents from a number of causes may occur at the elevator entrance. A person attempting to pass through the doorway 5 in the elevator, while the elevator is moving downwardly, may be caught between the top of the doorway 5 and the elevator landing. In this event, the striking member 15 will be actuated to transmit movement to the 25 stopping switch S , thereby quickly stopping the elevator. Under the same conditions, if the elevator is moving upwardly, a person may be caught between the floor of the elevator and the top of the doorway in the elevator shaft. One of the bars 24 would then be actuated to open the stopping switch S' . The bars 24 may also be actuated by a person's arm or foot projecting from the entrance 5 in the elevator. When the elevator 30 is moving downwardly, a person standing on one of the landings and leaning into the elevator shaft may be struck by the switch operating member 9, which will result in actuation of the switch S to stop the elevator. Or, 35 if the elevator is moving upwardly, a person leaning into the shaft will be struck by the switch operating member 12' at the top of the elevator. These operating members 9 and 12' are also adapted to strike a projection of any kind extending into the front 40 of the shaft.

A means for operating the elevator is illustrated diagrammatically in Fig. IV. 30 designates an electric motor having a power shaft 31 provided with a worm 32 meshing with a worm wheel 33 on a drum 34, around which the elevator operating cable 35 is wound. This is intended to illustrate a conventional means for operating the elevator. 35 A brake drum 36 (Figs. III and IV) is fixed to the operating shaft 31. Levers 37, mounted on pivots 38, are provided with brake shoes 39 adapted to engage the drum 36. A solenoid 40 is provided with oppositely disposed cores 41, which are pivoted to the

levers 37. Springs 42 are interposed between the ends of the solenoid and spring seats 43 at the upper ends of levers 37. These springs 42, acting upon the levers 37, tend to force the brake shoes 39 into engagement with the brake drum 36. However, the solenoid 40 may be energized to act upon the cores 41, thereby overcoming the force of springs 42 and releasing the brake shoes 39 from the brake drum.

75 The means for transmitting electrical energy to the motor 30 (Fig. III) comprises a main line conductor 44, which may lead directly to the motor, and a conductor consisting of sections 45, 45^a, 45^b, and 45^c, through 80 which current is conducted to or from the motor. In the diagram I have shown, the operator's switch 46 is adapted to connect the conductor 45^b to the conductor 45^c, and the safety switch S' is used to connect the 85 conductor 45^a to the conductor 45^b. 47 designates a stopping switch which normally connects the conductor 45 to the conductor 45^a. Branch conductors 48 connect the solenoid 40 to the conductors 44 and 45^c. When all 90 of the switches just referred to are closed, current will flow to the motor 30 and also to the solenoid 40. The solenoid will then be energized to release the brake, and the elevator will be driven by the motor 30. Under 95 normal conditions, the operator's switch 46 is actuated to start and stop the elevator.

When the safety switch S' is moved to its open position, the flow of current to the motor 30 and solenoid 40 will be discontinued, and the springs 42 will act upon the 100 levers 37 to force the brake shoes 39 into engagement with the brake drum 36. From the foregoing description, it will be apparent that the safety switch S' may be opened to 105 quickly stop the elevator. After the elevator has been stopped in this manner, it may in some cases be desirable to quickly place the operating mechanism under the control of the operator's switch 46. For example, it 110 may be necessary to move the elevator a slight distance to release a person who had been caught between the elevator and a portion of the shaft. The circuit including the conductors 45^a and 45^b is therefore provided 115 with branches 50 and 51 adapted to be connected to each other by a normally open auxiliary starting switch 52. This switch 52 may be closed to render the safety switch S' ineffective. If it is desirable to operate the 120 elevator while the safety switch S' occupies its open position, the auxiliary switch 52 is closed by hand, and the electric current will then flow through the switch 52, instead of through the switch S' .

125 The devices controlled by the safety switch S include an electromagnet 53, adapted to attract a pivotally mounted holding device 54 having a projection 55, which cooperates with a hook 56 on the switch arm 47. A 130

spring 57 tends to pull said switch arm 47 to its open position, but the switch is normally retained in its closed position by the action of the magnet-controlled holding device 54, 5 which cooperates with the hook 56. The magnet 52 is normally energized by current flowing through conductors 58, 59 and 59', the conductors 59 and 59' being normally connected by the safety switch S on the elevator. When this switch S is moved to its open position, the flow of current to the magnet 53 will be discontinued; the holding device 54 will then be freed from the magnet, and the spring 57 will throw the switch 47 10 to its open position. This will open the circuit leading to the motor 30 and solenoid 40, with the result of stopping the motor and applying the brakes to quickly stop the elevator. After the elevator has been stopped in this 15 manner, it cannot be again started by merely closing the safety switch S. Therefore, if the switch S is opened as the result of an accident, the elevator will be quickly stopped and it will not be accidentally started by 20 breakage of some part of the mechanism permitting the switch S to return to its closed position. To start the elevator it will be necessary to close the switch 47, and to retain said switch in its closed position it will 25 be necessary to properly engage the hook 56 with the projection 55, while the magnet 53 is energized to retain said projection 55 in interlocking engagement with the hook.

I have previously referred to a relatively 30 weak connection 16 (Figs. I and II), whereby the striking bar 15 is connected to the switch operating chain 12 through which motion is transmitted to the safety switch S. If an excessive movement is imparted to the striking bar 15, the weak connection 16 will be 35 broken, thereby preventing a person from being seriously injured by the force transmitted through the bar 15. If the weak connection 16 is broken, the safety switch S will 40 be restored to its closed position, but for the reasons just given this will not restore the switch 47 through which current is conducted to the motor 30 and solenoid 40.

I claim.

50 1. An elevator provided with a stopping device, a safety switch controlling said stopping device to automatically stop the elevator, and operating means for said safety switch comprising a thrust receiving abutment in the form of a movable member extending across the elevator entrance so as to

be engaged and actuated by a projection moving with the elevator, thereby transmitting movement from the elevator to said safety switch, and operating means carried by the 60 elevator door whereby said thrust receiving member is actuated when the door moves to its open position.

2. The combination of an elevator, a shaft provided with elevator entrances at different 65 elevations, each of said entrances being provided with a door, a stopping device whereby the elevator is stopped, a safety switch adapted to control said stopping device, and means whereby movement is transmitted 70 from all of said doors to actuate said safety switch, said means comprising a movable thrust-receiving abutment across each elevator entrance and operatively connected to said safety switch, and means carried by the 75 elevator doors whereby said thrust-receiving abutments are actuated when the doors are opened.

3. In an elevator provided with a stopping device, a safety switch controlling said 80 stopping device to automatically stop the elevator, an operating means for said safety switch comprising a movable member extending across the elevator entrance and connecting with said safety switch, said movable member being operably engageable by 85 the elevator door.

4. An elevator provided with a stopping device, a safety switch device carried by the elevator and controlling said stopping device 90 to automatically stop the elevator, and operating means for said safety switch device comprising elongated vertically movable striking members arranged transversely of the elevator shaft and carried by the elevator 95 so as to strike an obstruction projecting into the elevator entrance, one of said striking members being arranged across the doorway in the elevator, another being below the front of the elevator and another being above the 100 front of the elevator, a switch-operating member carried by the elevator to actuate said safety switch device, and flexible operating connections leading from all of said striking members to said switch operating 105 member to provide for the transmission of movement from said striking members to said safety switch device.

In testimony that I claim the foregoing I hereunto affix my signature.

GEORGE P. McDONNELL.
